Primary Examiner — Ricky Pham(74) *Attorney, Agent, or Firm* — Harness, Dickey & Pierce, P.L.C.(57) **CLAIM**

The ornamental design for a food waste disposer, as shown and described.

DESCRIPTION

FIG. 1 is a perspective view;

FIG. 2 is a front elevational view;

FIG. 3 is a rear elevational view;

FIG. 4 is a top plan view;

FIG. 5 is a bottom plan view;

FIG. 6 is a left elevational view; and,

FIG. 7 is a right elevational view.

The broken lines in all views are for the purpose of illustration and are not part of the claimed design.
